DISPENSING DEVICE

George Boden, Waterbury, Conn., assignor to
 Scovill Manufacturing Company, Waterbury,
 Conn., a corporation of Connecticut

Application December 18, 1934, Serial No. 757,999

9 Claims. (Cl. 312—74)

This invention relates to dispensers and more particularly to devices for dispensing articles mounted on strip material such, for example, as pins or the like.

Devices for this purpose are usually arranged to feed an article supporting strip step by step to successively place one article after the other in predetermined position to be seized by the operator. The usage to which such devices are subjected is frequently severe and an object of this invention is to provide a dispenser of the type set forth of such simple, rugged construction that it is adapted to give long continued service without interruption due to any mechanical defect, while avoiding the necessity for heavy or cumbersome parts.

This and other objects which will be apparent to those skilled in this particular art are attained by the invention hereinafter described and illustrated in the accompanying drawings in which,

Fig. 1 is a top plan view of a dispenser constructed in accordance with one embodiment of this invention, the central part of the supply roll being broken away so as to disclose the adjustable support therefor;

Fig. 2 is a side elevation of the mechanism shown in Fig. 1, parts thereof being broken away;

Fig. 3 is a view similar to Fig. 2 showing one side of the operating mechanism with the cover plate removed, the parts being in normal inoperative position;

Fig. 4 is a view from the front of Fig. 3;

Fig. 5 is a top plan view of the parts shown in Fig. 3, certain of the parts being in section;

Fig. 6 is a view similar to Fig. 3 showing the actuating mechanism in depressed position;

Fig. 7 is a transverse sectional view showing the parts in the position of Fig. 6;

Fig. 8 is a view similar to Fig. 3 showing the opposite side of the actuating mechanism;

Fig. 9 is a transverse sectional view on the line 9—9 of Fig. 8; and

Fig. 10 is a view similar to Fig. 6 showing the opposite side of the actuating mechanism;

The illustrated embodiment of the present invention comprises a base 11 having a pin 12 for rotatably supporting a supply roll 13 of pins 14 mounted in the conventional manner on paper tape 15. An adjustable support for holding the supply roll at different levels so as to accommodate rolls of different sized pins is provided by a roll supporting block 16 loosely mounted on the pin 12 and having a plurality of recesses 17 in the bottom thereof of different depths. By rotating the supporting block 16 to locate a supporting pin 18 in the correct recess 17, the block 16 is held at the required height to properly position the superimposed supply roll relatively to an associated feeding mechanism.

A strip feeding mechanism 19 is mounted upon

the base 11 at one side thereof and is spaced from the pin 12 a distance sufficient to accommodate the largest size supply roll 13 with which the mechanism will be used. The feeding mechanism is adapted to be manually operated and the arrangement is such that the operator's fingers are brought automatically together upon a pin which has been moved into position to be seized, and in such position has been partially ejected from the strip 15. A guide-way 20 for the pin holding strip is formed between vertically extending plates 21 mounted on the base 11. A feeding pawl 22 is pivotally mounted on a supporting slide 23 mounted for reciprocating movement in guides 24 formed by ears struck from the upper portion of one of the plates 21. A pawl spring 25 presses the pawl inwardly so that its inner end extends through a slot 26 in the supporting slide 23 and through a slot 27 in the supporting side plate 21. Feeding movement is imparted to the pawl by a slidable actuator 28 mounted for vertical sliding movement in guides 29 formed on the outer faces of the side plates 21. The pawl slide is provided with a lug 30 which extends into a cam slot 31 formed in the adjacent side of the actuator 28 so that vertical movement of the latter reciprocates the slide 23 and pawl 22 a distance sufficient to move the pins 14 successively into position to be seized. The actuator is normally held in elevated position by a spring 32 mounted on a supporting post 33 having one end extending through a spring lug 34 on the actuator, the spring being tensioned by having its other arm pressed against the base 11.

Associated with the actuator 28 for vertical movement therewith is an ejector for partially ejecting the pins from the paper strip and moving them into a position where their heads will be automatically seized by the fingers of the operator depressing the actuator 28. As illustrated, this ejector is formed by a yieldable spring finger 35 secured at its lower end to one side of the actuator slide 28 and having its upper end 36 bent inwardly into position to resiliently engage the shank of a pin below the pin head, see Figs. 3, 4 and 8. A pin guide 37 extends upwardly from one of the side plates 21 on the side of the pin opposite from the ejector 35, and the guide 37 is open on the side facing the ejector finger so that the movement of the pin as it is drawn partially out of the supporting paper strip is properly guided. A pin holding spring finger 38 is mounted on a bracket 39 and is adapted to move inwardly to engage the pin shank when the ejector is lowered, as shown in Figs. 7 and 10.

The top of the actuator 28 is formed by a circular presser plate 40 having a central perforation through which the partially ejected pin and the pin guide 37 project when the actuator is depressed by the operator. It will be apparent

that the thumb and forefinger of the operator are automatically positioned on opposite sides of the pin head which can be easily seized and withdrawn.

- 5 In operation the presser plate 40 is pushed downwardly by the operator. This downward movement shifts the feeding pawl 22 rearwardly a distance equal to the distance between successive pins on the paper tape. At the same time, 10 the operator's forefinger and thumb automatically seize the pin which is already in the guide 37 and which is held therein by the spring finger 38 being pressed against the shank of the pin by contact with a shoulder 42 below the presser 15 plate 40, see Figs. 4 and 7. The pin in the guide can then be extracted and in doing so the operator releases the presser plate 40 and actuator 22 so that the mechanism is raised by the spring 32. The first operation of the vertical movement causes the cam slot 31 and spring 43 to feed the pawl 22 forwardly a distance sufficient to locate the next succeeding pin in position beneath the pin guide 37. The remaining movement of the actuator 28 upwardly brings the 25 ejector finger 35 into contact with the pin under the head and raises it upwardly through the guide 37 into position to be seized upon subsequent depression of the presser plate 40. A spring pressed holding pawl 44 is mounted on 30 one of the side plates 21, see Figs. 8 and 9, and extends inwardly through a slot 45 for preventing retrograde movement of the pin strip 15.

Although the cam slot 31 which actuates the feeding pawl is illustrated as a closed slot capable 35 of moving the pawl in both directions, I prefer to employ the pawl spring 43 as this permits the use of a lighter spring 32 for moving the actuator so as to make the operation thereof easy and smooth. The mechanism is preferably 40 housed within a casing 46 and cover 47.

It will be apparent that the invention can be variously modified and adapted within the scope of the appended claims.

I claim:

- 45 1. A dispenser for articles mounted on strip material comprising in combination a base, a pin mounted on said base for rotatably holding a supply roll of material thereon, a dispensing and feeding mechanism mounted on said base and 50 spaced from said pin a distance sufficient to clear a supply roll on said pin, an adjustable support for a roll on said pin, and means for holding said support at different levels including a pin on said base engageable in recesses of different 55 depths in said support.
2. A dispenser for articles mounted on strip material comprising in combination an ejector for engaging an article and placing it in position to be seized, means for feeding said strip 60 to successively place the articles thereon in position to be engaged by said ejector, a manually operated presser plate connected to said ejector and movable to bring the operator's fingers into engagement with the article in position to be seized and to retract said ejector to engage another article.

3. A dispenser for articles mounted on strip material comprising in combination an ejector for engaging an article and placing it in position 70 to be seized, means for feeding said strip to successively place the articles thereon in position to be engaged by said ejector, a presser plate connected to said ejector and movable to bring the operator's fingers into engagement

with the article in position to be seized and to retract said ejector to engage another article, and a yieldable member for holding the article in position to be seized upon retraction of said ejector.

4. A dispenser for headed articles mounted on strip material comprising in combination an ejector for engaging the head of an article to partially eject it from said strip and place it in position to be seized, means for feeding said strip to successively position the articles thereon in position to be engaged by said ejector, and a manually operated perforated presser plate for actuating said ejector movable to bring the operator's fingers into engagement with the article 15 in position to be seized.

5. A dispenser for headed articles mounted on strip material comprising in combination a feeding mechanism for successively placing the articles on said strip in a predetermined position, 20 an ejector engageable with the shank of an article below the head thereof for partially ejecting said article from said strip and moving it into position to be seized, and a manually operated slide movable in a direction transversely 25 of the line of feed of said strip for actuating said ejector and said mechanism and for bringing the fingers of the operator into engagement with said partially ejected article.

6. A dispenser for articles mounted on strip material comprising in combination a strip feeding pawl, a guide, an ejector movable longitudinally of said guide for withdrawing an article from said strip and moving it along said guide into position to be seized, and a manually operated presser plate for actuating said ejector movable into position to permit seizure of said article.

7. A dispenser for articles mounted on strip material comprising in combination a strip feeding pawl, a guide, an ejector movable longitudinally of said guide for withdrawing an article from said strip and moving it along said guide into position to be seized, and a slidably mounted actuator for said pawl and said ejector including a perforated presser plate adapted to be moved into position around said guide to permit seizure of the article therein.

8. A dispenser for articles mounted on strip material comprising in combination a strip feeding pawl, a guide, an ejector movable longitudinally of said guide for withdrawing an article from said strip and moving it along said guide into position to be seized, a slidably mounted actuator for said pawl and said ejector including a perforated presser plate adapted to be moved into position around said guide to permit seizure of the article therein, and means for holding said article in said guide during movement of said actuator.

9. A dispenser for articles mounted on strip material comprising in combination a strip feeding pawl, a guide, an ejector movable longitudinally of said guide for withdrawing an article from said strip and moving it along said guide into position to be seized, a slidably mounted actuator for said pawl and said ejector including a perforated presser plate adapted to be moved into position around said guide to permit seizure of the article therein, and a yieldable member adapted to be engaged by said actuator and moved into engagement with the article in said guide upon movement of said actuator.

GEORGE BODEN.
